UNITED STATES PATENT OFFICE.

JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

HOPPER-CAR-DOOR-OPERATING MECHANISM.

1,109,598.

Specification of Letters Patent.

Patented Sept. 1, 1914.

Application filed March 29, 1912. Serial No. 687,225.

To all whom it may concern:

Be it known that I, JOHN M. ROHLFING, a citizen of the United States, residing at St. Louis, Missouri, have invented a certain new and useful Improvement in Hopper-Car-Door-Operating Mechanism, of which the following is a full, clear, and exact description, such as will enable others skilled in the art to which it appertains to make and use the same, reference being had to the accompanying drawings, forming part of this specification, in which—

Figure 1 is a side elevation of a portion of a hopper car, the doors of which are equipped with my improved operating mechanism. Fig. 2 is a cross sectional view taken approximately on the line 2—2 of Fig. 1. Fig. 3 is a cross sectional view similar to Fig. 2 and showing the doors dropped or lowered into dumping position. Fig. 4 is an enlarged detail section taken approximately on the line 4—4 of Fig. 1. Fig. 5 is an elevation of one of the hooks which serves as means for locking the ends of the door levers to the winding shaft.

This invention relates to new and useful improvements in operating mechanism for the doors of hopper cars, and the principal objects of my invention are, to provide simple means whereby both doors can be simultaneously actuated from a single shaft that can be operated from either side of the car, to provide a pair of levers which coöperate with the doors and support the free edges thereof when the same are dropped into dumping positions, to arrange hooks on the ends of the door levers, which hooks are connected to the winding chains so that the ends of said hooks are caused to engage with the winding shaft to hold the doors locked in closed position and to generally improve and simplify the construction of hopper car door-operating devices.

Referring by numerals to the accompanying drawings; 1 designates the side girders of the car body, the same being surmounted by side walls 2 and the ends of which girders rest upon the usual body bolsters 3.

4 designates the inclined plates which form the end walls of the car body.

The doors 5 are hinged at their outer edges in any suitable manner to brackets arranged beneath the girders 1, and said doors are designed to close against each other at their free edges. The ends of the

doors 5 are provided with depending wings or webs 7, preferably formed of sheet metal, and when the doors are closed, these webs occupy vertical positions immediately adjacent to the lower ends of the inclined plates 4.

Longitudinally disposed strengthening members 8, preferably in the form of I-beams, are fixed to the undersides of the doors and extend along the free edges thereof, and if desired, longitudinally disposed strengthening members 9 in the form of angles may be located upon the central portions of said doors.

10 designates the winding shaft, the same being journaled in suitable bearings 11 on the underside of one of the girders, and carried by one end of this winding shaft is a beveled pinion 12.

13 designates a transversely disposed operating shaft that is journaled in suitable bearings and extends from one side of the car to the other. Hand wheels 14 are fixed on the ends of this shaft 13, and a beveled pinion 14^a is also fixed on said shaft, which pinion meshes with the pinion 12.

Fixed on the winding shaft 10 adjacent to the end carrying the beveled pinion 12 is a ratchet wheel 15 with which is adapted to engage a pawl 16, the latter being pivotally connected to a fixed member of the car body.

Pivotally connected to brackets 17 that are located at the ends of one of the doors 5 beneath the free edge thereof are the ends 90 of transversely disposed door-operating levers 18, the same being provided on their upper edges with lugs 19 and 20.

Journalized in suitable brackets 21 at the ends of the door opposite the door to which the levers 18 are pivotally connected are rollers 22 which engage on the upper edges of the levers 18 during the opening and closing movements of the doors. When the doors are closed the rollers 22 engage behind the lugs 19, as shown in Fig. 2, and when the doors are open, as shown in Fig. 3, said rollers engage behind the lugs 20.

Pivotally mounted on the free ends of the levers 18 are hooks 23 each provided with a lug or a pair of ears 24, through which passes a pin 25 that engages the lower link of the corresponding winding chain or cable 26. The upper end of each hook 23 is curved inward, as designated by 23^a so as to

engage over the winding shaft 10 when the chains or cables are wound thereon, thereby securely holding the doors in closed positions. The upper curved end 23^a of each hook is provided with a laterally projecting lug 23^b against the front edge of which the corresponding winding chain or cable normally engages while the doors are being closed or during their opening movement, but when the doors are moved upwardly to their limit of movement the upward pull upon the winding chains 26 swings the inwardly curved upper ends 23^a of the hooks over the winding shaft 10, thereby holding said doors locked in their closed positions. When the doors are closed the various parts of my improved operating mechanism occupy the positions as seen in Figs. 1, 2 and 4. With the parts so positioned the lugs 19 bear directly against the rollers 22, thereby clamping the free edges of the doors in close relation and resisting any tendency of the free edges of said doors to spread apart. The free ends of the levers 18 are locked to the winding shaft 10 by the engagement of the hooks upon said winding shaft and said shaft is held against rotary movement which would permit the chains or cables to unwind, by the auxiliary locking means comprising the ratchet wheel 15 and pawl 16.

When it is desired to actuate the operating mechanism and permit the doors to swing downward into dumping positions the point of the pawl 16 is disengaged from the ratchet wheel 15, and when this is accomplished, the winding shaft 10 is slightly rotated in a direction reverse to the direction said shaft was rotated to wind the chains upon said shaft, and by such slight reverse rotation the upper ends of the hooks 23 are disengaged from said winding shaft by reason of their frictional engagement therewith. As soon as the hooks are thus disengaged the weight of the load acts to swing the doors downward into open, dumping positions, and during this opening movement the chains 26 unwind from the shaft 10 and the rollers 22 will ride over the lugs 19 and thence upon the upper edges of the levers 18, and when the doors have swung open to their limit of movement said rollers 22 occupy positions directly behind the lugs 19. When the pawl 16 is disengaged to permit the doors to swing downward the chains 26 will unwind from the shaft for a considerable distance and the ends of the levers 18 carrying the hooks will swing downward some little distance before the free edges of the doors start to move downward and away from one another for the reason that the rollers 22 are bearing against the lugs 19. When the rollers 22 finally pass over lugs 19 the weight of the load on the door upon which the rollers 22 are mounted will cause said door to drop with considerable force

onto the levers 18, thereby producing pounding effect which tends to loosen the load and cause the same to free itself from the interior of the car body.

The doors are swung upward and closed by manually engaging either one of the hand wheels 14 and actuating the same to impart rotary motion to the shaft 13. This rotary motion is transmitted by means of the beveled pinions 12 and 14^a to the winding shaft 10, and as said shaft is rotated the chains 26 are wound thereon, consequently pulling the levers 18 upward and moving the free edges of the doors toward one another. During this closing movement of the doors the pull of the chains connected to the lower ends of the hooks 23 tends to swing the upper ends of said hooks inwardly, but by reason of the engagement of the flanges 23^b at the upper ends of said hooks against the chains, said hooks are maintained in upright position, as seen in Fig. 5, until the upper portions of said hooks are drawn above the winding shaft 10, and the continued pull upon the chains now automatically swings the hooks upon their points of pivotal connection with the levers 18 and the upper ends of said hooks are thus engaged over said winding shaft (see Fig. 4). When the upper portions of the hooks pass above the winding shaft the continued pull of the chains on the lower ends of said hooks tends to swing the same upon the pins that pivot said hooks to the ends of the levers 18, and thus said hooks are automatically moved into engagement with the winding shaft.

It will be readily understood that in some instances where a comparatively short car is equipped with my improved door-operating mechanism that only one lever and winding chain or cable will be necessary, and where such arrangement is carried out the lever is positioned midway between the ends of the doors. In some instances it may be found desirable to connect the levers by an equalizing bar, and to arrange on said bar one of the winding shaft engaging hooks, which latter is connected to the shaft by a single winding chain or cable.

A car door-operating mechanism of my improved construction is comparatively simple, comprises a minimum number of parts, can be actuated to close the doors from either side of the car, and the hooks that form a connection between the winding chains and the levers are automatically thrown into engagement with the winding shaft to lock the doors in closed position by the final movement of the operating mechanism.

It will be readily understood that minor changes in the size, form and construction of the various parts of my improved car door-operating mechanism can be made and substituted for those herein shown and de-

scribed without departing from the spirit of my invention, the scope of which is set forth in the appended claims.

I claim:

1. The combination with a pair of oppositely moving doors for closing the opening in a hopper car, of a lever pivotally connected to one of the doors near the free edge thereof, and coöperating with the opposite door, and means for moving the lever longitudinally and pressing it against the last mentioned door to close the same.

2. The combination with oppositely moving doors for closing the opening in a hopper car, of a lever pivotally connected to one of the doors near its free edge, which lever coöperating with the free edge of the opposite door, and means for swinging the lever to close the first mentioned door and simultaneously exert pressure upon the last mentioned door to close the same.

3. The combination with the doors of a hopper car, of a lever pivotally connected to one door near its free edge and slidably supporting the free edge of the opposite door, a catch member pivotally mounted on the free end of the lever, and means for moving the lever to close the doors and finally operate the catch member to secure the doors in closed position.

4. The combination with the hinged doors of a hopper car, of a lever pivotally connected to one of the doors near its free edge, which lever supports the free edge of the opposite door, a hook pivotally mounted on the free end of the lever, a winding shaft in position to be engaged by the hook when the doors are closed, a flexible connection between said winding shaft and the hook, and means on said hook and normally engaging the flexible connection for holding said hook in position to engage the winding shaft when the doors are closed.

5. The combination with a pair of hopper car doors, of a lever supporting the free edges of said doors, which lever is pivotally connected to one of said doors, a shaft at the side of the car, a hook carried by the free end of the lever and adapted to engage said shaft when the doors are closed, and a connection between the free end of the lever and the winding shaft, whereby said lever will be raised to close the doors.

6. The combination with a pair of oppositely opening doors, of a lever pivotally connected to one of the doors and slidably supporting the free edge of the opposite door, anti-friction means between said last mentioned door and the lever, and means for tilting the lever to close the doors.

7. The combination with a pair of hopper car doors, of a lever pivotally connected to one of the doors near its free edge, a roller bearing on the opposite door near its free edge, which roller bearing engages the lever,

lugs on said lever against which the roller bearing engages when the doors are closed and open, and means for elevating the lever to simultaneously close the doors.

8. The combination with a pair of hopper car doors, of a lever pivotally connected to one of the doors near its free edge, a roller bearing on the opposite door near its free edge, which roller bearing engages the lever, lugs on said lever against which the roller bearing engages when the doors are closed and open, a winding shaft, and a flexible connection between said winding shaft and the free end of the lever.

9. The combination with a pair of oppositely opening doors, of a lever arranged beneath the free edges of the doors, which lever is pivotally connected to one of said doors and slidably fulcrumed on the free edge of the opposite door, and means whereby said lever is elevated to close the doors.

10. The combination with a pair of swinging doors, of a lever arranged beneath the free edges of the doors, which lever is pivotally connected to one of said doors and slidably fulcrumed upon the free edge of the opposite door, actuating means whereby said lever is swung to close the doors, and means operable by said actuating means for locking the door-operating mechanism when the doors are closed.

11. The combination with a pair of swinging doors, of a lever pivotally connected to one door and coöperating with the opposite door, actuating means for moving the lever to close the doors, and means operable by the actuating means for locking said lever when the same has been shifted to close the doors.

12. The combination with a pair of hopper car doors, of a winding shaft arranged for operation at the side of the car, connections between said winding shaft and the free edge of the door on the opposite side of the car from said shaft, and means carried by said connections for engaging the shaft to lock the doors in closed positions.

13. The combination with a pair of pivot-ed hopper car doors, of levers pivotally connected to the free edge of one door near the ends thereof, which levers coöperate with the opposite door, actuating means for simultaneously moving the levers to close the doors, and means operable by the actuating means for locking the doors in closed position.

14. The combination with a pair of oppositely opening hopper car doors that are hinged at the sides of the car body, of a winding shaft, a movable connection from the free edge of one door to the winding shaft, which connection extends transversely beneath the other door and constitutes the sole support for the free edges of the doors, and means for actuating said

connections to simultaneously swing the doors in opposite direction.

15. The combination with a pair of hopper car doors that are hinged at the sides of the car body, of a winding shaft, connections from the free edge of one door to the winding shaft, which connections extend beneath one of the doors, means for actuating said connections to simultaneously close the doors, and means for locking the connection actuating means when the doors are closed.

16. In a car, the combination with a pair of oppositely movable doors for closing a discharge opening, of a door-operating means including a lever fulcrumed on one of said doors, the fulcrum point being variable longitudinally of the lever, and means for actuating the lever to vary the fulcrum point.

17. The combination with a pair of oppositely movable hopper car doors for closing a discharge opening, of a door-operating means including a lever positively connected to one door, and which lever has a movable fulcrum on the opposite door.

18. The combination with a pair of oppositely movable hopper car doors for closing a discharge opening, of a door-operating means including a lever pivotally connected with an inner part of one door, and which lever has a movable fulcrum on the opposite door.

19. The combination with a pair of oppositely movable hopper car doors for closing a discharge opening, of a door-operating means including a lever connected with one door and lapping the other door, which lever is fulcrumed on the opposite door, the fulcrum point being variable.

20. The combination with a pair of oppositely movable hopper car doors for closing a discharge opening, of a door-operating means including a lever pivoted on one door and extending beyond the free edge of the other door, and which lever is fulcrumed on the last mentioned door.

21. In a car, the combination with a pair of oppositely movable doors for closing a discharge opening, of a door-operating means including a lever connected near the

meeting edges of said doors, and which lever employs one of said doors as a movable fulcrum.

22. In a car, the combination with a pair of oppositely movable doors for closing a discharge opening, of a lever pivotally connected to one door and engaging the opposite door, means for actuating said lever to move the doors into closed position, a pair of shoulders formed on the lever, and means on the door that is engaged and supported by the lever for engaging the shoulders on said lever when said doors are closed and open.

23. In a car, the combination with a pair of oppositely movable doors for closing a discharge opening, of a lever pivotally connected to one of said doors, and engaging against and supporting the opposite door, means for actuating the lever to close the doors, a shoulder on the lever, and means on the door engaged and supported by the lever for engaging the shoulder on said lever when the doors are closed.

24. In a car, the combination with a pair of oppositely movable doors for closing a discharge opening, of a lever pivotally connected to one of said doors, and engaging against and supporting the opposite door, means for actuating the lever to close the doors, a shoulder on the lever, and means on the door engaged and supported by the lever for engaging the shoulder on said lever when the doors are open.

25. In a car, the combination with a pair of oppositely opening doors, of an actuating lever for said doors, said lever being pivoted to one of said doors and coöperating with the free edge of the other of said doors, means for swinging the free end of said lever to close the doors, and means on said lever for engaging the last mentioned door to clamp the free edges of the doors together upon the final movement of the lever.

In testimony whereof I hereunto affix my signature in the presence of two witnesses, this 18th day of March, 1912.

JOHN M. ROHLFING.
